DESIGN FOR A DRESS

Charlotte Marie Neuhardt, New York, N. Y.

Application April 3, 1940, Serial No. 91,421

Term of patent 3½ years

To all whom it may concern:

Be it known that I, Charlotte Marie Neuhardt, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design;

Fig. 2 is a rear view thereof, and

Fig. 3 is a fragmentary view of Fig. 1 illustrating the dress in open position at neck.

The characteristic feature of my design resides in the combination on the fly front dress disclosed of the specific pocket members, each of said pockets comprising a smaller pocket centrally disposed on a larger pocket as shown.

I claim:

The ornamental design for a dress, substantially as shown and described.

CHARLOTTE MARIE NEUHARDT.
